UNITED STATES PATENT OFFICE

2,623,329

EXTENSIBLE DOLL

Anthony Di Leva, Brooklyn, N. Y.

Application March 31, 1950, Serial No. 153,051

2 Claims. (Cl. 46—161)

1

My invention relates to dolls and, more particularly, to dolls with movably connected members.

Objects of my invention are to provide a doll with extensible members, for example, with an extensible neck and with extensible limbs, in such a manner that the length of these members can be easily changed, thereby to make possible changes in the appearance of the doll, in its size and in its proportions, and thereby to provide a novel and entertaining toy.

Other objects are to make possible rotation of members or of parts of members about an axis parallel to the direction of extension, to provide ball joints allowing adjustment of these members or of other members connected to the same in various directions of the space, and to amplify the variety of possible positions of the members by these means.

A further object is to provide frictional engagement between the movable parts of the doll whereby these parts will stay in any of the adjusted positions.

Still other objects are to prevent separation of the movable parts, and thereby to prevent loss of parts or members.

Still further objects are to attain these results with simple means and to provide a doll having the mentioned properties which can be made inexpensively.

Still other objects and advantages will appear from the following description of an exemplifying embodiment of my invention, from the appended claims and from the accompanying drawing in which:

Fig. 1 shows a front view of an illustrative embodiment of my invention, the extensible members being represented extended about half as much as possible.

Fig. 2 shows a cross-section taken along the line 2—2 in Fig. 1 and representing a broken off part of the embodiment shown in Fig. 1.

Fig. 3 shows a cross-section taken along the line 3—3 in Fig. 1 and representing another broken off part of the same embodiment.

Fig. 4 shows a cross-section taken along the line 4—4 in Fig. 1 and representing a third broken off part of the same embodiment.

Figs. 2 to 4 are represented on a larger scale than Fig. 1.

Referring to the drawing, numeral 1 indicates the trunk of the doll, including shoulders 5 and upper leg portions 6. The trunk 1 may be hollow and has three vertical cylindrical openings, one in its upper side and two in the lower side of the leg portions 6.

2

An extensible neck extends from the upper side of the trunk and comprises a plurality of telescopically connected parts, for example, two parts 7 and 8. The part 7 passes slidably through the upper opening of the trunk 1 and forms a tube having a lower end provided with a flange 9 which forms a stop preventing complete extraction of the part 7 from the trunk. The upper end of this neck part has an inwardly projecting rim 11. The part 8 passes slidably through the opening surrounded by the rim 11 and has a lower end provided with a flange 12 which forms a stop preventing complete extraction of the part 8 from the part 7.

15 A head 13 is connected to the upper end of the part 8. This connection is preferably constituted by a ball joint which may be constructed in any known and suitable manner. For example, the part 8 terminates in a ball 14 which is snapped into a correspondingly shaped recess in the lower side of the head 13. The opening of this recess is slightly smaller than the largest diameter of the ball 14.

20 Similarly constructed ball joints may connect the shoulder portions 5 with arm parts 15 which have ball-shaped ends 16 secured in recesses of the shoulder portions. Each part 15 has a cylindrical inner space terminating in a slightly narrower opening at that end of the part 15 which is opposite to the ball 16. Another arm part 17 passes slidably through this opening and has a stop flange 18 at its inner end. A hand 19 may be affixed or connected to the other end of the part 17.

25 Each leg may be formed, for example, of three telescopically connected parts. One of these parts is constituted by the upper leg portion 6 which has a cylindrical inner space extending farther up into the trunk 1 and having a lower circular opening narrowed by a rim 21. Another leg part 22 passes slidably through this opening and forms a tube provided with a stop flange 23 at its upper end and with an inner rim 24 at its lower end. A third leg part 25 passes slidably through the opening surrounded by the rim 24 and forms a cylinder provided with a stop flange 26 at its upper end.

30 The lower end of the part 25 is connected to a foot or shoe 27. This connection may be constituted by a ball joint comprising a ball 28 forming an integral part of the foot 27 and by a corresponding recess in the lower end of the leg part 25.

35 The described neck, legs and arms form members each of which can be extended or shortened by shifting parts of each member in the direction

of their common axis. The head, the hands and the feet form other members which are not immediately connected to the trunk, but indirectly by extensible members whereby these other members are distant from the trunk. The positions of these distant members are varied by the variation of the lengths of the extensible members and can be additionally varied by rotation of one shiftable part relatively to another, and further by turning the balls of the ball joints in their respective recesses. The extensible parts and the parts of the ball joints contact with a friction that can be easily overcome when the parts are moved relatively to each other but that is sufficiently large to prevent dislocation of these parts by their own weight or by only slight force whereby the parts will readily stay in any of the possible mutual positions.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters Patent is:

1. A doll comprising a trunk having circular openings narrowed at their entrance by an internal rim, a limb assembly for each of said trunk

openings including a first part slidable in the trunk opening and having a stop flange frictionally engaging the wall of the opening and adapted when extended to engage the internal rim of the circular opening thereby to limit its outward movement thereof, said first part being hollow and narrowed at its outer end by an internal rim, a second part slidable in the first part and having a stop flange frictionally engaging the internal wall of the first part and adapted when extended to engage the internal rim of the first part thereby to limit its outward movement therefrom, said first and second parts telescoping with respect to each other and with respect to the trunk and being rotatably adjustable with respect to each other and with respect to the trunk.

2. A doll defined in claim 1 and a third part and ball and socket means connecting the third part to the outer end of the second part.

ANTHONY DI LEVA.
